DESIGN FOR A CENTRIFUGAL PUMP

John M. Little, Toledo, Ohio, assignor to Barnes
Manufacturing Co., Mansfield, Ohio, a corpora-
tion of Ohio

Application December 30, 1944, Serial No. 117,195

Term of patent 14 years

(Cl. D65—1)

To all whom it may concern:

Be it known that I, John M. Little, a citizen of the United States and a resident of Toledo, Lucas County, Ohio, have invented a new, original, and ornamental Design for a Centrifugal Pump, of which the following is a specification, reference being had to the accompanying drawing, forming a part thereof.

In the drawing:

Figure 1 is a perspective view of a centrifugal pump showing by new design;

Figure 2 is a side view of the design; and,
Figure 3 is a front elevation of the same.

I claim:

The ornamental design for a centrifugal pump, substantially as shown.
